UNITED STATES PATENT OFFICE.

HERBERT W. MARTIN, OF BENNINGTON, VERMONT.

FOOT-PROTECTOR.

SPECIFICATION forming part of Letters Patent No. 253,402, dated February 7, 1882.

Application filed October 12, 1881. (No model.)

To all whom it may concern:

Be it known that I, HERBERT W. MARTIN, of Bennington, in the county of Bennington and State of Vermont, have invented certain new and useful Improvements in Foot-Protectors; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved foot-protector, and Fig. 2 is a cross-section through the top part of the same.

Similar letters of reference indicate corresponding parts in both the figures.

My invention contemplates an improvement in foot-warmers or foot-protectors, as herein-after more fully described, and particularly pointed out in the claim.

In the annexed drawings, A represents the body of my improved foot-protector, which is by preference made of sheepskin with the wool on. Around the rim *a* on the outside, flush with the top edge of the same, is stitched a band of textile gathered fabric, B, and next to this again is stitched another piece of textile fabric, C, which is doubled around or over the top edge, *a*, and stitched to the inside of the rim, its lower edge being doubled around the inner bottom edge of the band B to form a ribbed seam or welt, *b*. The band B on the outside is doubled around the lower edge of band C to form a pouch or bag around the outside of the top rim of the protector for the in-

sertion of an elastic web, D. Thus it will be seen that web D is confined on one side by the band C and on the other (the outside) by the band or doubled fabric B. In other words, on the outside and around the top rim of the protector there are four thicknesses of material—to wit, the fabric B, band C, web D, and doubled outer edge of fabric B—while on the inside there are two thicknesses—viz., the doubled or overlapping bands C and B, which are stitched together and to the material A by the seam *b*. This makes a re-enforced top rim of the protector, prevents undue wear or chafing of the elastic web in putting the protector on or off, prevents (by the ribbed seam or welt *b*) ripping of the band B from the inside of the top, and forms a convenient means for contracting the top of the protector so as to retain it in its proper position upon the leg, the inelastic bands B and C being “gathered” to permit of the expansion of the elastic web D.

Having thus described my improvement, what I claim, and desire to secure by Letters Patent of the United States, is—

A foot-protector having an elastic opening made up of the parts A B C, and an elastic, D, all arranged and connected as shown and described.

In testimony that I claim the foregoing as my own I have hereunto affixed my signature in presence of two witnesses.

HERBERT W. MARTIN.
